EXPANDING ANCHOR

Elmer K. Cole, Centralia, Mo., assignor to A. B.
Chance Company, Centralia, Mo., a corporation
of Missouri

Application January 30, 1943, Serial No. 474,082

3 Claims. (Cl. 189—92)

The present invention relates to expanding anchors, and is particularly concerned with the provision of improved expanding anchors of the type adapted to be carried by a guy rod, inserted into a bored hole in the earth, and thereafter expanded by tamping.

One of the objects of the present invention is the provision of an improved expanding anchor of the class described, which is adapted to be constructed out of non-metallic material for the purpose of conserving metals required for other essential purposes during the war effort.

Another object of the invention is the provision of an expanding anchor of the class described, which may be constructed of wood, and which is adapted to be manufactured with a minimum amount of labor.

Another object of the invention is the provision of an expanding anchor of the class described, which is adapted to exert a maximum resistance to the pull of the guy rod, and in which the anchor wings are automatically separated and driven into predetermined anchoring position by tamping the top of the anchor assembly on the guy rod.

Other objects and advantages of the invention will be apparent from the following description and the accompanying drawing, in which similar characters of reference indicate similar parts throughout the several views.

Referring to the single sheet of drawings accompanying this specification:

Figure 1 is a diagrammatic elevational view of the anchor shown in the anchor hole after the assembly has been tamped to spread the anchor wings into engagement with the side walls of the bore in the earth;

Fig. 2 is a fragmentary side elevational view of the anchor assembly as it appears before it has been tamped and before it is inserted into the anchor hole in the earth;

Fig. 3 is a top plan view of the anchor assembly of Fig. 2 with the guy rod in section;

Fig. 4 is a side elevational view of the anchor assembly of Fig. 2 looking from the right hand side of Fig. 2;

Fig. 5 is a fragmentary elevational view of the expanding anchor assembly of the type shown in Figs. 1 to 4;

Fig. 6 is a view similar to Fig. 2 of a modification in which the anchor wings are made of one integral piece of material adapted to be split or separated by a spreading action of the wedge.

Referring to Fig. 1, 10 indicates in its entirety an anchor assembly carried by a guy rod 11 and

located in a diagonally expanding bore 12 in the earth. The guy rod may be of any convenient type, but it is preferably of the type having a lower threaded end 13 and provided with a nut 14 threaded on this end of the guy rod for engaging the lower face of the anchor assembly. The upper end of the guy rod is preferably provided with some form of eye structure for receiving a cable of which the guy is constructed.

The anchor assembly preferably comprises a wedging member 15 and a pair of expanding wings 16, 17. The wedge member 15 may consist of a substantially cylindrical wooden body, preferably constructed of relatively hard and tough wood such as oak, the body being provided with an axially extending bore 18 for passing the guy rod 11. The lower face 19 of the wedging member 15 is preferably plane for engaging the upper thrust surface 20 of the nut 14, but in some embodiments of the invention the lower surface 19 may be of other appropriate conformation.

The wedging body 15 is preferably provided with a pair of beveled camming surfaces 21, 22 located diametrically opposite to each other and extending from a point adjacent the lower face 19 to the upper surface 23 of the wedge 15. These beveled camming surfaces 21, 22 give the cylindrical body of the wedge 15 a tapered conformation when seen in side elevation from one side as shown in Fig. 2, but the camming surfaces 21, 22 take the form of conic sections when seen from the other two sides as shown in Fig. 4.

The camming surfaces 21, 22 are also preferably plane surfaces for slidably engaging the anchor wings 16, 17 and spreading them from the position of Fig. 2 to that of Fig. 5. The anchor wings 16 and 17 may be similar in size and shape, but they are oppositely located on the guy rod 11.

Each of these anchor wings may comprise a substantially half-cylindrical wooden member preferably constructed of the same wood as the wedge 15, and provided with an axially located partially cylindrical groove 24, adapted to receive the anchor rod when the halves are assembled on it. The two wings 16 and 17 may have the groove of such depth that there is a substantial crack 25 between the halves when assembled on the guy rod 11, as shown in Fig. 3.

At their lower ends the two wings 16 and 17 are also preferably provided with beveled camming surfaces 26, 27 for engaging the upper corners 28, 29 of the wedge 15 and initiating the expanding action. These camming surfaces 26, 27 are also preferably plane surfaces. The wings 16, 17 are preferably assembled on the guy rod by

providing a frangible band 30 extending around the wings and holding them in camming engagement with the guy rod 11 above the wedge 15, as shown in Fig. 2. This frangible band 30 may consist of a suitable wire or cord which is adapted to hold the wings in position until they are placed in the bore 12 in the earth ready for the tamping action.

Referring to Fig. 6, this is a modification in which the two wings 16, 17 form legs of one integral member indicated by the numeral 31. This member has an axially extending slot 32 which extends upward over a substantial portion of its length, and gives the member 31 a tendency to split in half when it is subjected to the spreading action of the wedge 15. In such case the frangible band 30 may be omitted.

Referring to Fig. 5, this view shows the anchor in its expanded position with the wings 16 and 17 driven into the side walls of the earth surrounding the bore 12.

The operation of my earth anchor is as follows:

The bore 12 is preferably of only slightly larger size than the external diameter of the wing assembly 16 and 17, shown in Fig. 2 or Fig. 6. Thus the anchor wings are ready to engage the side walls of the bore as soon as any tamping action takes place and the anchor is adapted to utilize the engagement of the wings with the undisturbed earth surrounding the bore 12, since this portion of the earth is adapted to exert a greater resistive action.

The assembly is placed upon the guy rod 11, as shown in Fig. 2 or Fig. 6, and using the guy rod as a handle, the wings and wedging member are inserted to the bottom of the bore 12.

The tops of the wings 16 and 17 are then engaged by a tamping member, preferably of considerable weight and of substantially the same shape so as to utilize the full end area of the wings, the tamping member having a slot for receiving the guy rod. The tamping then drives the wings downward, and their lower ends are cammed outward by the engagement of the sloping surfaces 26, 27 with the corners 28, 29. The tendency is for the band 30 to hold the upper portions of the wings together. As soon as the corners 28, 29 pass off the surfaces 26, 27, the wings 16 and 17 are acted on by the camming surfaces 21, 22. The wings 16, 17 are then guided downward and outward by the camming surfaces 21 and 22, to the position of Fig. 5, where these wings are driven into the side walls of the undisturbed earth to effect a secure anchoring action. The anchor assembly is then covered with rocks and earth filling the bore 12, the fill being tamped downward to make it as compact as possible. The frangible band breaks or the body splits as the wings spread.

The present anchor assembly has the advantage that it utilizes only wood in one of its embodiments and a minimum amount of metal in other embodiments where a metal band might be employed. It could be manufactured and sold at a relatively low cost as a substitute for the earth anchors of the prior art, which were usually made of metal such as no longer may be available as long as metal is required for the manufacture of arms. Even where metal is available, the present anchor may be constructed at a lower cost, as it is adapted to provide a maximum resistance against movement in proportion to its cost.

While I have illustrated a preferred embodiment of my invention, many modifications may be made without departing from the spirit of the invention, and I do not wish to be limited to the precise details of construction as set forth, but desire to avail myself of all changes within the scope of the appended claims.

Having thus described my invention, what I claim as new and desire to secure by Letters Patent of the United States is:

1. An earth anchor comprising a substantially cylindrical wedging body having an axially extending bore for receiving a guy rod, said wedging body having diametrically opposite sides thereof provided with beveled camming surfaces approaching each other toward the top of the wedging body, and a wing assembly comprising an integral member adapted to be split into a pair of separable members when driven onto the wedging body, said member having an axially extending bore for receiving the guy rod, said separable members being shaped to engage the beveled surfaces on said wedging body whereby they may be guided and driven into embedding engagement with the walls of earth or the like surrounding the bore in which the anchor is placed, said separable members being integrally joined together and formed of one integral cylindrical member provided with an axially extended slot.
2. An earth anchor comprising a substantially cylindrical wedging body having an axially extending bore for receiving a guy rod, said wedging body having diametrically opposite sides thereof provided with beveled camming surfaces approaching each other toward the top of the wedging body, and a wing assembly comprising a pair of separable members having an axially extending bore for receiving the guy rod, said separable members being shaped to engage the beveled surfaces on said wedging body whereby they may be guided and driven into embedding engagement with the walls of earth or the like surrounding the bore in which the anchor is placed, said separable members being bound together by a frangible band adapted to hold the separable members together at the top said band being adapted to be broken when the wing assembly is driven down against the wedging body.
3. In an earth anchor, the combination of a guy rod provided with a lower threaded end and a threaded member carried by said end, with a substantially cylindrical wooden member having a pair of oppositely located plane beveled sides forming a wedge, said wooden member having an axially located bore receiving said guy rod, with a wing assembly comprising two wing portions joined by a frangible connection at the top, said connection being breakable by driving the wings against the wedge so that the wings spread into two separate parts, said assembly being slidably mounted on said guy rod above said first wooden member, said wing assembly being formed in its lower surface with a pair of beveled surfaces engaging the upper corners of said first wooden member and adapted to initiate the spreading action of the parts of said wing assembly whereby tamping on the upper plane surface of said wing assembly causes it to spread into two parts, increasing the effective size and engagement of said anchor with the earth.
